UNITED STATES PATENT OFFICE.

JOSEPH AUGUST SKOGLUND, OF ST. PAUL, MINNESOTA.

BRUSH.

1,373,455.

Specification of Letters Patent. Patented Apr. 5, 1921.

Application filed January 15, 1920. Serial No. 351,716.

To all whom it may concern:

Be it known that I, JOSEPH AUGUST SKOGLUND, a subject of the King of Sweden, residing at St. Paul, in the county of Ramsey 5 and State of Minnesota, have invented a new and useful Improvement in Brushes, of which the following is a specification.

This invention relates to improvements in hair brushes and more particularly to that 10 class employing a flexible back upon which the bristles are mounted. This back can be folded or flexed with the bristles pointing inwardly and the ends of the flexed portions secured by a strap which performs the double 15 function of a handle when the back is unfolded for using the brush and of a fastener for releasably securing the ends of the brush in folded condition.

In the accompanying drawing forming 20 part of this specification, Figure 1 is a perspective view of my invention looking at the bristle side; Fig. 2 is another perspective view looking at the back of the brush; Fig. 3 is another perspective view when the brush 25 is folded, and Fig. 4 is a cross section of a detail showing a few of the bristles and the manner of securing them to the back.

In the drawing, A indicates the back of 30 my improved brush made out of plies B or several thicknesses of pliable material, stitched at C together. Secured to the inner face of this back through the inner ply (see Fig. 4) are bristles D composed of angularly shaped thin flexible wires the outer 35 ends of which incline in the same general direction. The flexible back is adapted to fold or flex inwardly as shown in Fig. 3 over the bristles in which position a flexible strap E made of leather or other suitable

material is adapted to encircle and hold the 40 back. The ends of this strap have a separable spring fastener F by which the strap is secured to hold the back folded. The body of the strap is secured near its ends by the stitching C to the back leaving the intermediate portion loose or free so that the hand of the user can be inserted to hold and use the brush when the fastener F has been released.

The device forms a convenient brush for 50 use by travelers and the flexibility of the back increases its efficiency in use both as a hair or other brush and when it is desired to fold and pack the brush away. The strap also as applied to the brush performs 55 the double function of a handle and a fastening means for securing the brush in folded position.

Having described my invention what I claim as new and desire to protect by Letters 60 Patent is:

A brush, comprising, in combination, a flexible back having bristles on its under side, a strap forming a handle portion above the back and having an attaching tab freely 65 extended from one end of said back, the handle portion of said strap being attached at its extremities near the ends of the back, a fastening member on the extremity of said handle portion opposite the tab and a 70 companion fastening member on the free end of said tab, said strap serving both as a handle and as an encircling medium to secure the back in folded relation.

In testimony whereof, I have signed my 75 name to this specification.

JOSEPH AUGUST SKOGLUND.
